INVENTOR:

Andrew J. Beulings

UNITED STATES PATENT OFFICE.

ANDREW J. HEWLINGS, OF CHICAGO, ILLINOIS.

NON-CONDUCTING PIPE-COVERING.

SPECIFICATION forming part of Letters Patent No. 664,950, dated January 1, 1901.

Application filed April 21, 1900, Serial No. 13,829. (No model.)

To all whom it may concern:

Be it known that I, ANDREW J. HEWLINGS, a citizen of the United States, residing in Chicago, in the county of Cook and State of Illinois, have invented certain new and useful Improvements in Non-Conducting Pipe-Coverings, of which the following is a specification.

The object of my invention is the production of a non-conducting covering for high and low temperature pipes of maximum strength and durability, economical to manufacture, and such that it may utilize with maximum effectiveness such non-conductors as air-spaces more or less strictly confined, and the various non-conducting materials especially available for the commercial manufacture of non-conducting coverings for steam, hot-air, gas, water, and other pipes and conduits.

My invention consists, primarily, in multiple separate or separable and individual segmental units made of suitable pliable paper or felt materials, non-conducting material, each an angular tube and conformed to the curvature of the surface to be protected, each sealed or unsealed at the ends, each constituting either an individual air-space or an individual receptacle for non-conducting materials, all arranged and assembled in one or more layers, into sections of hollow cylindrical covering, the aforesaid individual segmental units being held together between an outer and an inner stiffening-shell of suitable non-conducting material by cement, paste, glue, or silicate of soda, and the sections of hollow cylindrical covering thus produced being further connected one with another by an outside sheath of suitable cloth or like fabric adapted to hinge and connect one such section with another, so as to facilitate the application of the whole to the pipe sought to be covered and protected. Preferably the aforesaid segmental units are each of the largest possible size consistent with their economical manufacture, in pliable paper or felt materials, and with the required rigidity of the finished product, and preferably the said segmental units being more or less tubular in form are as far as practicable arranged to break joint with one another longi-

tudinally, so as to attain the maximum rigidity for the assembled whole.

My invention also consists in the combination, with the foregoing, of suitable extensions or flaps of one or more layers of the inner shell of each section of hollow cylindrical covering adapted to fold over either edge of such section and be cemented down beneath the outside sheath above named, and to thus finish the edges of each section in a clean and workmanlike manner, so that such edges shall fit neatly and closely upon the like edges of adjacent sections when the whole non-conducting covering is applied to the cylindrical surface sought to be covered and protected.

The accompanying drawings, forming a part of this specification, show the general plan and nature of my invention, although it is not limited to the precise details of form and proportion therein appearing.

Figure 1 is a perspective view of a complete covering of but one layer of segmental units applied to a pipe, but with sufficient part of the outside sheath and outer shell removed to show the segmental non-conducting units in position. Fig. 2 is a longitudinal section through line *x* *x* on Fig. 1, and Fig. 3 is a transverse section through line *y* *y* on Fig. 1. Fig. 4^a is one of the segmental non-conducting units with sealed ends. Fig. 4^b is the same with open ends, and Fig. 4^c is the latter segmental unit as it appears filled with a non-conducting material instead of simply constituting an air-space. Fig. 5 is a perspective and transversely-sectional view of an entire portion of complete covering laid open ready for application to the pipe to be protected.

Like letters of reference indicate like parts in all the figures.

A A A are segmental units, each constituting either a sealed dead-air space or a more or less open circulative air-space or a compact receptacle for non-conducting filling B, such as mineral wool, silica fiber, asbestos fiber, or such other non-conducting or insulating materials, as peculiar conditions of service may require.

C is the inner shell in one or more layers, fitted to the curvature of the pipe to be cov-

ered, and made, like the segmental units and the outer shell, of asbestos paper, asbestos millboard, asbestos felt, wool felt, or other non-conducting or insulating papers or cloth fabrics or a combination of the same.

D D are the extensions or flaps of one or more layers of the inner shell C, folded over the free edges of the sections of covering, and cemented over the outer shell E and under the outside sheath F, and adapted to finish such edges, as before described. The outside sheath F is of cloth or like fabric and is adapted by the hinge connection G and the overlap H to attach together the sections of hollow cylindrical covering and facilitate the application of the whole to the pipe K sought to be covered and protected.

All the aforesaid parts are secured to each other in their assembled form by silicate of soda, paste, glue, or other suitable cement.

In prior devices in this art air spaces or receptacles for insulating filling materials have been formed in various manners by means of fluted, indented, channeled, or corrugated paper or cloth fabrics and by means of variously built-up chambers, and also insulating materials have been variously woven or molded into compact sections or masses adapted to form non-conducting coverings; but in no instance has a removable sectional covering been formed of multiple separate and individual tubular segmental units of pliable paper or felt materials adapted to the insulation of ordinary high and low temperature pipes conformed to the curvature of the pipe and adapted to constitute individual sealed dead-air spaces or open circulative air spaces or receptacles for insulating filling materials.

Air-space properly confined is well known to be the nearest possible approach to perfect heat insulation, and by my construction it is possible to economically manufacture a non-conducting covering for ordinary high and low temperature pipes in which there is the requisite rigidity and at the same time the largest possible amount of inclosed air-space in proportion to the thickness of the whole covering, together with means of applying the covering to such pipes in an effective and workmanlike manner.

Air-chambers built of brick, terra-cotta, and other plastic materials have been used for insulating large cylindrical surfaces, such as boilers, but such devices are wholly impractical for ordinary pipes, such as steam and hot or cold water pipes, which require a removable envelop of strictly pliable and not plastic or friable material. In some instances, such as the covering of certain high-temperature pipes, it is essential that the insulating-air, though confined laterally, shall have somewhat free circulation longitudinally in the direction of chimney-conduits to the outer atmosphere, and in such instances the sealing of the ends of the tubular segmental units is conveniently omitted. As combina-

tion receptacles for air and insulating filling materials the individual segmental units of pliable paper or felt materials have the commercially-important feature of being adapted to the consumption of the short-fiber domestic asbestos that is found in great quantities within the United States, but that cannot be successfully woven into fabric or molded into rigid masses, as can the much more costly long-fiber foreign asbestos. The individual segmental units are readily filled with this short-fiber material, and I thus utilize it to form a rigid and permanent non-conducting pipe-covering, whereas the pipe-coverings now manufactured with molded masses of the said short-fiber material soon deteriorate and fall to pieces under their own weight. Further, in all adaptations of the individual segmental units it is an important consideration that the puncture or breakage of one or more units can affect only the particular units so injured, and, again, the close contact of the walls of adjacent units constitutes a keystone-arch construction that gives special rigidity and resistance.

The preferable construction of overlapping the edges of each section of covering with the extensions from the inner shell supplies an especially effective finish and strengthening for each section and lessens the liability to injury through careless handling in applying the covering to the pipe to be protected.

Having thus described my invention, and set forth certain of the advantages thereof, I now claim—

1. In a non-conducting pipe-covering, in combination, multiple separate and individual tubular segmental units of pliable paper or felt materials, conformed to the general curvature of the pipe and constituting separable insulation-chambers, and means for binding the said segmental units into rigid sections of covering to sheath the pipe substantially as specified.

2. In a non-conducting pipe-covering, in combination, multiple separate and individual tubular segmental units of pliable paper or felt materials, conformed to the general curvature of the pipe and constituting separable insulation-chambers, and inner and outer shells, properly cemented with said segmental units and binding said units into rigid sections of covering to sheath the pipe, substantially as specified.

3. In a non-conducting pipe-covering, in combination, multiple separate and individual tubular segmental units of pliable paper or felt materials, conformed to the general curvature of the pipe and constituting separable insulation-chambers, and inner and outer shells, properly cemented with said segmental units and binding said units into rigid sections of covering, and an outside sheath of fabric holding said rigid sections together and facilitating their application to the pipe, substantially as specified.

4. In a non-conducting pipe-covering, in combination, multiple separate and individual tubular segmental units of pliable paper or felt materials, conformed to the general curvature of the pipe and constituting separable insulation-chambers, and inner and outer shells, properly cemented with said segmental units and binding said units into rigid sections of covering to sheath the pipe, and extensions or flaps from the inner shell folded over and finishing the edges of the said rigid sections, substantially as specified.

5. In a non-conducting pipe-covering, in combination, multiple separate and individual tubular segmental units of pliable paper

or felt materials, conformed to the general curvature of the pipe and constituting separable insulation-chambers, and inner and outer shells, properly cemented with said segmental units and binding said units into rigid sections of covering, and an outside sheath of fabric holding said rigid sections together and facilitating their application to the pipe, and extensions or flaps from the inner shell folded over and finishing the edges of the said rigid sections, substantially as specified. 20 25
